FEEDING DEVICE FOR SHEET MATERIAL

Ernst C. Sauerman, Chicago, Ill.

Application June 5, 1948, Serial No. 31,338

10 Claims. (Cl. 101—132.5)

1

This invention relates to improvements in a feeding device for feeding folded sheet material from a hopper or the like to a pair of coating rolls, and refers particularly to a feeding device for feeding folded printing cards from a hopper to a pair of pressure rolls where said card is brought into printing or duplicating relationship with a continuously advancing web to imprint indicia from said printing cards upon said web.

One of the objects of the present invention resides in the provision of means for periodically removing the lowermost folded sheet from a stack of such sheets and conveying the removed sheet forwardly to an operating station.

Another important object of the invention resides in the provision of means for conveying the folded sheets aforesaid from the stack of sheets to the operating station at a predetermined linear speed, and feeding said sheets in the operating station between opposed rolls whose peripheral speed is different from the speed of feeding whereby said sheets pass between said rolls in overlapping relationship.

An important feature of the invention comprises means for overlapping the sheets between the rolls which can be conveniently changed to change the degree of overlap of the sheets between the rolls.

Another important feature of the invention resides in means which positively conveys the sheets forwardly to the operating station at a predetermined speed and which disengages from said sheets at the moment or slightly prior thereto that the sheet is brought under the control of the slower moving conveying elements at said station, whereby injury to the sheet is prevented at the period of transition of traveling speeds of the sheet.

Another important object of the present invention resides in the provision of a folded sheet or card which can be employed as a printing card, said card being readily engageable by the conveying means hereinbefore mentioned and from which the conveying means can be readily and quickly disengaged, the card carrying transferable indicia which are protected during use of the card in the machine from smearing adjacent cards during removal of the card from the stack; the card is also constructed that the indicia carried thereon are so positioned as to permit a maximum degree of overlapping at the printing station.

Other objects and advantages of the present invention will be apparent from the accompanying drawings and following detailed description.

In the drawings,

2

Fig. 1 is a side elevational view of my improved machine.

Fig. 2 is a plan sectional view taken on line 2—2 of Fig. 1.

Fig. 3 is a detailed view of one of the sheet-engaging fingers about to disengage itself from a folded sheet.

Fig. 4 is a sectional view taken on line 4—4 of Fig. 3.

10 Fig. 5 is a longitudinal sectional view taken on line 5—5 of Fig. 2.

Fig. 6 is a transverse sectional view taken on line 6—6 of Fig. 1.

Fig. 7 is a detailed view of one of the engaging fingers about to be reset to engaging position.

Fig. 8 is a sectional view taken on line 8—8 of Fig. 7.

Fig. 9 is a view similar to Fig. 8 showing the position of the finger at a phase shortly after that illustrated in Fig. 8.

20 Fig. 10 is a detailed plan view of the conveyor illustrating the function and operation of the conveyor fingers.

Fig. 11 is a face view of the bottom card of 25 an inverted stack of printing cards usable with the present machine.

Fig. 12 is an end view of the card shown in Fig. 11.

Fig. 13 is a view of the reverse face of the card illustrated in Fig. 11.

30 Fig. 14 is a sectional view of an inverted stack of cards, taken on line 14—14 of Fig. 11.

Referring particularly to the drawings, 1 indicates the base of my improved machine, a pair of side frame members 2 being mounted upon said base in vertical position and in spaced parallel relationship. The side frame members 2 are maintained in spaced relationship by means of transverse bar 3 which may be secured to the opposite frame members by means of bolts or the like 4. The frame members 2 are also interconnected by transverse rods 5 and 6, shown best in Figs. 2 and 6.

A shaft 7 is journaled at its opposite ends in the opposite frame members 2 and a second shaft 8 is similarly journaled at the opposite end of the machine. A pair of sprocket wheels 9 are carried upon the shaft 7 and are disposed adjacent the inner faces of the side members 2. Similarly a pair of sprocket wheels 10 are carried upon shaft 8 adjacent the inner faces of the side members 2 and in alignment with the respective sprocket wheels 9 upon shaft 7.

An electric motor 11 is mounted upon base 1 adjacent the machine, said motor being coupled 55 with a conventional speed reducing mechanism

12. The output shaft 13 of the speed reducer 12 carries a grooved pulley 14 over which a belt 15 is trained. Shaft 8 on one side of the machine extends outwardly from its supporting frame member 2 and carries a grooved wheel 16 over which the belt 15 is also trained whereby shaft 8 is rotated by the motor 11.

A sprocket chain 17 is trained around one pair of sprocket wheels 9 and 10 and a sprocket chain 18 is similarly trained around the remaining pair of sprocket wheels 9 and 10, the path of travel of the sprocket chains at their upper passes being adjacent the upper edges of the frame members 2.

A pair of upwardly extending standards 19 are secured to the opposite frame members 2 adjacent one end of the machine. This end of the machine will hereinafter be referred to as the delivery end. A shaft 20 is journaled at its ends in bearings 21 carried by the opposite standards 19, and one end of said shaft extends outwardly from one of the standards. Gear wheel 22 is mounted upon the outwardly extending end of the shaft 20, said gear wheel being adapted to engage with pinion 23 carried upon the end of shaft 8. A rubber covered roll 24 is mounted upon an intermediate portion of shaft 20 for purposes which will be hereinafter more fully described.

A steel or other hard surfaced roll 25 is positioned beneath roll 24 in slightly offset vertical relationship with said latter roll. Roll 25 is carried upon a shaft 26, the opposite ends of which are journaled in the ends of a pair of bell crank levers 27 and 28, shown best in Fig. 6. The bell crank lever 27 is journaled intermediate its length upon a stub shaft 29 carried by one of the frame members 2 and the bell crank lever 28 is journaled intermediate its length upon a similar shaft 30 carried upon the opposite frame member 2. Coil springs 31 are connected respectively at their ends to the ends of the bell crank levers 27 and 28, and both of said springs are anchored upon rod 6 at their opposite ends, as shown best in Fig. 5.

The arrangement is such that roll 25 is urged upwardly into pressure contact with roll 24 by means of the tension in springs 31, said springs tending to rock levers 27 and 28 upon their respective shafts 29 and 30.

Broadly, the primary function of my invention is to feed sheet material forwardly from a supply station to an operating station. The character of the sheet material which is fed forwardly may vary, as for instance, it may comprise printing units, that is, elements which may be used to transfer indicia carried by said units to another sheet or web, or said sheet material may comprise units which are adapted to be printed upon, such as envelopes. In each case, of course, the character of the operating station will vary. For example, if the sheet material units which are fed forwardly comprise printing units, the operating station may comprise simple pressure rolls between which the units transfer their indicia to a sheet or web which may be passed between the rolls in company with the units. If the sheet material units comprise elements which are to be printed upon, such as envelopes, the operating station may comprise type-carrying rolls, or printing elements which print upon the envelopes fed forwardly. Obviously, therefore, my invention in its broadest aspect is not to be limited to the specific type of elements fed forwardly or the specific function of the operating station to which the elements are fed.

From the physical point of view, apart from specific function, the units fed forwardly are relatively flat so that they can be conveniently stacked and may comprise cardboard, paper, Cellophane or like plastic sheet material, thin metal or the like, and they are so constructed as to provide a channel, a fold in the case of a cardboard card or the like, whereby conveying members may engage to carry the same forwardly. From a physical aspect the operating station, apart from its function, preferably comprises rotating members which act to carry the unit delivered thereto forwardly in addition to performing a specific function such as pressing, printing or the like.

For purposes of illustrating the operation of my invention, the unit employed comprises a printing card. Reference is specifically made to Figs. 11, 12, 13 and 14. In the drawings a card 32 is illustrated as comprising a flat sheet of relatively thin cardboard which is folded intermediate its length to form a flap 33 and is folded adjacent the opposite end to form a panel 34. The panel 34 is adhesively secured to the main card body 35, said portion of the card being provided with an elongated aperture 36, one side of which is defined by the fold 37 which joins the flap to the main body 35. The inner face of the flap comprises a portion 38 which appears through the aperture 36. Upon that portion 38 of the flap which is visible through aperture 36, indicia 39 are carried, the indicia comprising information which may be inscribed upon the portion 38 by an ink which can be rendered transferable when moistened with a predetermined liquid.

A plurality of cards 32 are adapted to be stacked, as shown best at 40 in Figs. 1 and 5 in a hopper 41. The hopper 41 may comprise frame members 42 which define a space so dimensioned as to accommodate the cards 32. The frame members comprising the hopper 41 are secured by means of brackets 43 (Fig. 2) to the cross bar 3, the brackets 43 being provided with slots 44 in which screws 45 are positioned whereby the hopper 41 may be adjustably positioned relative to the length of the machine.

Adjacent the rear end of the hopper, that is, the end which is secured to the brackets 43, the frame members are bent inwardly and upwardly as shown best at 46 in Fig. 5 whereby the lowermost card 32 of the stack 40 is carried adjacent the edge of the card 32 which carries panel 34.

A pair of T-shaped brackets 47 are secured to the cross bar 5 adjacent the forward end of the hopper 41. Cross portions 48 of the T-shaped members 47 are secured to the upright portions of the T-shaped members by means of screws 49. An end 50 of each of the cross members 48 projects beneath the forward portion of hopper 41 and is spaced from the lower portion of said hopper. It can readily be seen that when the stack 40 of cards 32 is positioned in the hopper, the stack being arranged with the flaps 33 of the cards disposed downwardly, the lowermost card is supported along one edge by the inturned flanges 46 and the opposite edge of the card is supported by the ends 50 of the cross members 48. However, as the cards approach the lowermost position, the lowermost card slides laterally in offset relationship to the stack 40 as shown best at 51 in Fig. 5 whereby the flap 33 drops by gravity so as to dispose the flap at an acute angle to the main body portion 35 of the lowermost card 32. The position of the hopper 41 with respect to the chains 17 and 18 is such that the

flap 33 drops to a position between the upper passes of said chains.

A plurality of blocks 52 are positioned upon each chain 17 and 18, the blocks on each chain being spaced from each other and the blocks on opposite chains being in alignment with each other. Each block 52 carries a bell-crank lever 53 having a finger 54 and an arm 55, the bell-crank lever in each case being pivotally secured to a block by means of screw 56. A pin 57 is carried upon each block between finger 54 and arm 55 and functions as a stop to limit the position of either finger 54 or arm 55 when said lever is pivoted about screw 56, as will be hereinafter more fully described.

A rail 58 is mounted upon the top of each side frame member 2 and is secured thereto by means of screws 59 which pass through slots 60 provided in each rail whereby said rails can be adjusted and secured in a desired adjusted position longitudinally along said frame members. It will be noted that one end of each of the rails 58 is positioned above the sprocket wheels 9 and the opposite ends of the rails are disposed along a transverse line in advance of the nip between rolls 24 and 25. The purpose and importance of this positioning of the rail ends, or more strictly speaking, of the rails themselves will be hereinafter more fully described.

A pair of chain-supporting tracks 61 are mounted upon the inner faces of the side frame members 2, one track being positioned in supporting relationship with each chain at its upper pass, each chain riding upon a truck. At the end of the machine adjacent the operating station an arcuate plate 62 is positioned adjacent each chain, said plates at their upper portion are each secured, by means of a screw 63 or the like to the inner face of track 61. At their lower portion the plates are secured to the opposite frame members 2 by means of screws 64, the plates being spaced from the inner faces of the frame members by means of block 65 through which screws 64 pass. By means of tracks 61 and blocks 65 the plates are disposed with their outer faces adjacent the inner sides of the chains.

In the operation of the device, when the motor 11 is energized, the sprocket wheels 18 act to drive the sprocket chains 17 and 18. It will be noted that the sprocket chains are so disposed that their outer lateral faces are positioned adjacent the inner faces of the respective frame members 2. Consequently, during the lower pass of said chains, arms 55 are maintained parallel to the inner faces of the frame members, that is said arms are disposed parallel to the length of the chains. Consequently, the fingers 54 of the levers 63 are disposed at right angles to the length of the chains and extend inwardly toward each other.

As the chains move and a pair of blocks 52 pass beneath the hopper 41, the fingers 54 carried by the opposite blocks engage in the fold of the lowermost card 32, that is, the fold made by the connection of the flap 33 and main body portion 35 of the card. It will be noted that the lowermost card, in shifting laterally with respect to stack 40, causes the flap of said card to swing downwardly, opening up the fold to a predetermined degree and thereby permitting the ready entrance of the fingers 54 into engagement with said fold. As the chains move forwardly, the lowermost card 32 is thus extracted from the stack 40 and is carried forwardly by the engagement of the fingers 54 in the fold of the card. 75

In view of the fact that the lowermost card 32 is removed from the stack 40 in a sliding fashion, there would be a tendency for the typed material 39 upon the lowermost card to smudge the rear face of the flap 33 of the card immediately above during the sliding motion. This tendency is completely avoided by the fact that the depth of the typed material 39 that is, its thickness upon the surface of the flap 33 is less than the thickness of the card proper and, hence, the main body 35 of the card protects the typed matter 39 from coming into contact with the rear face of the flap of the card immediately above.

15 In addition, as can readily be seen by reference to Fig. 5, by virtue of the manner in which cards are supported in the hopper, the flap 33 of the lowermost card drops downwardly and, consequently, that portion of the flap which carries the typed matter 39 is removed from the rear face of the flap of the card immediately above. Consequently, although the ink or other matter employed to form the type 39 may be of appreciable thickness, and may readily be removed by contact 20 or abrasion, it is protected from such removal both by the structure of the hopper and by the structure of the card itself.

25 After leaving the hopper the card 32 engaged by the fingers 54 is carried forwardly by the chains. The levers 53 during engagement with the fold of the card 32 are prevented from being rocked by virtue of the drag offered by the card because of contact of the arms 55 with the rails 58. Just before the card enters the nip of the rolls 24 and 25 or simultaneously therewith, the fingers 55 of the levers 53 contact upstanding edges 66 of plates 62, said edges being disposed in the path of travel of the fingers 54. When such contact is made the levers 53 have travelled 30 beyond the ends of the rails 58 and, consequently, said levers are rocked about their pivot points 56 so as to dispose the fingers 54 parallel to the chains 17 and 18. It will be noted, therefore, that the fingers 54 are retracted from the fold of the card 32 simultaneously with or immediately prior 35 to the card being delivered to the nip of rolls 24 and 25.

40 The limiting positions of the fingers 54 by virtue of their contact with the edges 66 are determined by the pins 57. The opposite blocks 52 after passing beyond the rolls 24 and 25, are carried around the sprocket wheels 10. When said blocks enter upon the lower pass of the chains, the arms 55 are contacted by the rear edges of the frame members 2 and, hence, the levers 53 are again rocked to operative position, that is, that position wherein the fingers 54 are disposed at right angles to the length of the chains 17 and 18.

45 As a feature of my invention, the drive of roll 24 is so constructed that the peripheral speed of said roll is materially slower than the linear speed of the chains 17 and 18. Consequently, the cards carried by the chains move rapidly 50 from the hopper to a point immediately in front of the nip of the rolls 24 and 25. However, when said card enters the nip, its motion is slowed down appreciably to the rate of the peripheral speed of the roll 24. The peripheral speed of the roll 24 relative to the linear speed of chains 17 and 18 is preferably such that a plurality of cards will be positioned in the nip of the rolls 24 and 25 at all times, said cards being disposed in said nip in overlapping relationship. Of course, the number of pairs of blocks 52 carried by the chains 55

also enters as a factor in determining the number of overlapping cards which pass through the nip in a predetermined period of time. It is to be understood, of course, that as many pairs of blocks 52 as desired may be employed, since the number of overlapping cards in the nip can be controlled by the relative speed of the chains and the peripheral speed of the roll 24.

The desired overlap of the cards in the nip of the rolls 24 and 25 is such that the fold of one card within the nip, that is, the fold between the main body of the card 35 and the flap 33, is disposed along the opposite longitudinal edge of the aperture 38 from the edge which comprises a continuation of the fold of the card immediately beneath. Preferably the width of the cards is such that three or four cards will be disposed in overlapping relationship between the rolls 24 and 25. However, the number of cards disposed in overlapping relationship in the nip is a factor which can easily be determined by any one skilled in the art to adopt the machine to a predetermined operation.

It can readily be seen that one of the important advantages of my invention resides in the fact that cards may be withdrawn from the hopper 41 and carried forwardly at a relatively rapid rate; the card can then be slowed down in its passage between rolls 24 and 25 so that an adequate printing or transferring operation may be performed. Yet, although the cards during a major portion of their travel from the hopper to the rolls, are positively conveyed, the agency which engages the cards retracts from the fold of the cards immediately upon the delivery of the cards to the nip.

As another feature of my invention, it will be noted that the lowermost roll 25 is offset forwardly from roll 24. As the cards are carried forwardly by the chains 17 and 18, they are disposed substantially parallel to the plane of the upper pass of the chains which usually is horizontally. When, however, the cards are engaged by the rolls 24 and 25, the forward portion of the cards are canted upwardly by the overset rolls and, hence, the next card entering the nip will be disposed above the preceding card in the nip without jamming and with a minimum of wear upon the cards.

Although the lower roll 25 may be of a length greater than the transverse dimension of the card, the upper roll is preferably of a length slightly less than the length of the aperture 38. The purpose of this arrangement will be herein-after more fully described.

A pair of triangular frame members 67 are mounted upon the upper portions of standards 19 being secured thereto by bolts 68 which, between the standards carry a spacer sleeve 69. A shaft 70 is journaled at its ends at one corner of each of the frame members 67 and carries a reel 71 between said members. A similar reel 72 is carried by a shaft 73 which is journaled in an adjacent corner of each frame member. Reel 72 carries a roll of paper from which a web 74 is drawn; passed around sleeve 69 and around roll 24; and thence wound upon reel 71.

It will be noted that the cards 32 are so disposed in passing between rolls 24 and 25 that the type members 39 face upward. Hence, in passing between said rolls said cards come into printing relationship with web 74. A pulley 75 is carried upon reel 72 and a smaller pulley 76 is carried upon reel 71 and a belt 77 is trained around both pulleys. When roll 24 rotates, tension is set up

in the web 74 between roll 24 and reel 72 and said reel is rotated. Rotation of reel 72 tends to rotate reel 71 whereby the web passing from roll 24 to reel 71 is tensioned and wound upon reel 71. By virtue of the different sized pulley wheels 75 and 76, reel 71 will always tend to move at an angular speed greater than reel 72. Hence, regardless of the quantity of web wound upon reels 71 and 72, that is, the winding or unwinding diameter of the rolls, web 74 between rolls 24 and reel 71 will always be taut. Of course, at certain times slippage of the belt 77 is contemplated.

The type characters 39 carried upon the inner faces of the flaps 33 of cards 32 comprises a material which is rendered transferable by liquid. The liquid, which may comprise water, alcohol or other like solvent may be carried in a cup 78 carried by a fitting 79 which may include a sight-glass 80, the fitting 79 being mounted upon one of the triangular frame members 67 by means of a bracket 81. A flexible tube 82 may connect the fitting 79 to a web moistener 83 supported upon a rockable bar 84 journaled at its ends in opposite standards 19.

The web moistener 83 comprises a relatively flat housing 85 which is open along one side. The opposite side carries a nipple 86 which connects with the flexible tube 82. A wick 87 comprising an absorbent material such as felt or the like is positioned within the housing 85 and has an edge portion which protrudes from the open edge of the housing. A pin 88 is mounted upon a collar 89 which, in turn, is rigidly mounted upon bar 84, said pin, at its end, being connected to coil spring 90 anchored at its opposite end upon a second pin 91 carried upon one frame member 2. The arrangement is such that spring 90 tends to rock bar 84 in a clockwise direction, as viewed in Fig. 5, thereby bringing the protruding edge of the wick 87 into contact with the face of web 74 while said web is carried around roll 24. Thus, the face of the web is moistened with a liquid which will effect the transfer of the type 39 to the face of the web when the web meets the cards in the nip of rolls 24 and 25.

By virtue of the fact that roll 24 is of a length less than the length of aperture 38, said roll and the web 74 carried thereby are brought into intimate contact with the face of the typed indicia 39 unimpeded by the main body portion 35 of the card, that is, the pressure exerted by springs 31 in forcing roll 25 toward roll 24 is brought to bear directly upon the typed portion of the flap 33 without the interpositioned thickness of the main body portion 35 of the card.

It is desirable in transferring the impression of indicia 39 upon web 74 that the individual indicia of adjacent units 32 be spaced, in transfer, as closely as possible upon web 74, hence, the desirability of overlapping the units in the operating station and also the desirability of positioning the aperture 38 in each card as close as possible to the leading edge of the card.

Another feature of the card construction which is of importance is that the flap 33 is shorter in width than the main body 35 of the card and that the panel 34, when the card is in collapsed position, as shown best in Fig. 12, is disposed with its edge closely adjacent the free edge of the flap 33. By this arrangement the cards are of substantially uniform thickness throughout and, hence, when stacked, as in the hopper 41, the individual cards will occupy a substantially horizontal position throughout the height of the stack and will not be canted at a cumulatively chang-

ing angle from the bottom of the stack to the top thereof.

After the cards 32 have passed between rolls 24 and 25 they are discharged from the nip of said rolls onto conveyor belts 92 which are trained around shaft 8. A support 93 is mounted upon base 1 by means of a hinge 94 and at the opposite end of said support a pair of standards 95 are positioned which support a roller 96 over which belts 92 are also trained. A delivery platform 97 having an inclined portion 98 provides means for accumulating the cards traveling upon the belts 92.

Although my invention has been described in conjunction with an operation wherein printing cards are fed forwardly to an operating station to print impressions on a moving web, my invention broadly contemplates the feeding forwardly of impression members of any type or the feeding of such sheet material units as envelopes or the like, wherein the units are fed at a predetermined speed to an operating station wherein the speed of the units is reduced, the units moving through the operating station in overlapped relationship in a continuous or uninterrupted manner. In the case of printing cards being fed into contacting printing engagement with a moving web, both the cards and web move in a continuous and uninterrupted manner.

I claim as my invention:

1. A machine of the class described comprising laterally spaced means for carrying unit printing elements forwardly in spaced relationship to each other, a pair of opposed pressure rolls rotating about axes disposed transverse to the movement of said carrying means having a nip into which said units are fed, means for rotating said rolls at a predetermined peripheral speed, means for passing a web through the nip of said rolls, said nip being straddled by said laterally spaced carrying means, and means for moving said carrying means at a linear speed greater than the peripheral speed of said rolls to pass said printing elements between said rolls in overlapping relationship with each other and in printing relationship with said web.

2. A machine of the class described comprising means for carrying unit printing elements forwardly in spaced relationship, a pair of opposed pressure rolls laterally disposed with respect to said carrying means between which said units are fed, said rolls having an axes transverse to the direction of travel of said carrying means, means for rotating said rolls at a predetermined peripheral speed, means for passing a web between said rolls, and means for moving said carrying means at a linear speed greater than the peripheral speed of said rolls to pass said printing elements between said rolls in printing relationship with said web.

3. A machine of the class described comprising an endless conveyor for carrying units of folded sheet material with the fold foremost, members carried upon said conveyor for engaging in the fold of one of said units to pull the unit forwardly with the conveyor, a pair of opposed rolls, means for driving said rolls at a predetermined peripheral speed, means for moving said conveyor at a linear speed greater than the peripheral speed of said rolls, said conveyor being adapted to carry said unit to the nip of said rolls whereby the folded portion of said unit is grasped in the nip of said rolls, and means for disengaging said members from the fold of said unit immediately before said unit is grasped by said rolls.

4. A machine of the class described comprising a pair of laterally spaced endless conveyors for carrying units of sheet material, members carried upon said conveyors for engaging one of said units to carry the unit forwardly with the conveyors, a pair of opposed rolls one of which is disposed between said conveyors, means for driving said rolls at a predetermined peripheral speed about axes disposed transverse to the direction of travel of said conveyors, means for moving said conveyors at a linear speed greater than the peripheral speed of said rolls, said conveyors being adapted to carry said unit to the nip of said rolls whereby said unit is grasped in the nip of said rolls, and means for disengaging said members from said unit immediately before said unit is grasped by said rolls.

5. A machine of the class described comprising an endless conveyor, means for moving said conveyor in endless fashion, means upon said conveyor for releasably engaging a printing card, a pair of opposed rolls, means for rotating said rolls in timed relationship with the movement of said conveyor, said conveyor being adapted to deliver said card to the nip of said rolls wherein the card is grasped and carried forwardly by said rolls, means adjacent said conveyor for disengaging said card engaging means when said card is grasped by said rolls, and means for passing a web between said rolls in printing relationship with said printing card.

6. A machine of the class described comprising an endless conveyor, means for moving said conveyor in endless fashion, fingers pivotally carried upon said conveyor for engaging in the fold of a folded printing card, a pair of opposed rolls, means for rotating said rolls in timed relationship with the movement of said conveyor, said conveyor being adapted to deliver said card to the nip of said rolls wherein the card is grasped and carried forwardly by said rolls, means adjacent said conveyor for rocking said fingers about their pivots to disengage the fingers from the fold of the card when the card is grasped by the rolls, and means for passing a web between said rolls in printing relationship with the printing card.

7. A machine of the class described comprising an endless conveyor including a pair of parallel endless flexible members disposed in spaced relation to each other, a pivoted finger carried by each member in transverse alignment with each other for engaging in the fold of a folded printing card, a pair of opposed rolls adjacent the end of one pass of the conveyor, means for moving said conveyor in endless fashion, means for moving said rolls in timed relationship with the movement of the conveyor, said conveyor being adapted to deliver said card to the nip of said rolls wherein the card is grasped and carried forwardly by said rolls, means adjacent said conveyor for rocking said fingers about their pivots to disengage the fingers from the fold of said card when the card is grasped by the rolls, and means for passing a web between said rolls in printing relationship with the printing card.

8. A machine of the class described comprising an endless conveyor including a pair of parallel endless flexible members disposed in spaced relation to each other, a pivoted finger carried by each member in transverse alignment with each other for engaging in the fold of a folded printing card, a pair of opposed rolls adjacent the end of one pass of the conveyor, means for moving said conveyor in endless fashion, means for moving said rolls at a peripheral speed different from

the linear speed of said conveyor, said conveyor being adapted to deliver said card to the nip of said rolls wherein the card is grasped and carried forwardly by said rolls, means adjacent said conveyor for rocking said fingers about their pivots to disengage the fingers from the fold of said card when the card is grasped by the rolls, and means for passing a web between said rolls in printing relationship with the printing card.

9. A machine of the class described comprising an endless conveyor, means for moving said conveyor in an endless fashion, means upon said conveyor for releasably engaging a printing card carrying indicia formed from a liquid-transferable inscribable material, a pair of opposed rolls, means for rotating said rolls in timed relationship with the movement of said conveyor, said conveyor being adapted to deliver said card to the nip of said rolls wherein the card is grasped and carried forwardly by said rolls, means adjacent said conveyor for disengaging said card engaging means when said card is grasped by said rolls, means for passing a web between said rolls in printing relationship with said printing card, and means for moistening said web before the same enters the nip of the rolls.

10. A machine of the class described comprising an endless conveyor for carrying units of folded sheet material with the fold foremost, members carried upon said conveyor for engaging in the fold of one of said units to pull the unit forwardly with the conveyor, a pair of opposed rolls, means for driving said rolls at a predetermined peripheral speed, means for moving said conveyor at a linear speed greater than the peripheral speed of said rolls, said conveyor being

adapted to carry said unit to the nip of said rolls whereby the fold of said unit is initially grasped in the nip of said rolls, and means for disengaging said members from said unit at substantially the same time said unit is grasped by said rolls.

ERNST C. SAUERMAN.
